UNITED STATES PATENT OFFICE.

ROBERT W. SCOTT, OF PHILADELPHIA, PENNSYLVANIA.

TRIMMING FOR THE EDGES OF FABRICS.

SPECIFICATION forming part of Letters Patent No. 412,546, dated October 8, 1889.

Application filed June 14, 1888. Serial No. 277,089. (No specimens.)

To all whom it may concern:

Be it known that I, ROBERT W. SCOTT, a citizen of the United States, and a resident of Philadelphia, Pennsylvania, have invented 5 certain Improvements in Trimming for the Edges of Fabrics, of which the following is a specification.

My invention consists of a cheap substitute for the expensive hand-crocheted ornamental 10 borders or edgings, such as are now applied to knitted and other fabrics.

In the accompanying drawings, Figure 1 is a diagram on an enlarged scale, illustrating 15 my invention; and Fig. 2, a sectional diagram on a still larger scale.

It is now a common practice to finish the edges of knitted fabrics, and especially such as are used in making articles of underwear, by forming an ornamental crocheted border 20 upon such edges by hand, and it has recently been proposed to form ornamental borders by means of a crochet-machine; but the objection to the first plan is its expense, and to the second the limited range of patterns 25 which can be produced and the slow working of the machine as compared with the speed of the machine when used for plain work.

In order to overcome these objections, I 30 knit or otherwise form strips *x*, each comprising an outer scalloped or other ornamental border or edging, an inner straight bar, and spaced cross bars or pillars connecting said inner bar and the outer scalloped 35 portion, as shown in the drawings, and then secure these strips to the edge of the fabric *y*, forming the garment by means of a series of crochet or overedge stitches *w*, which will permit the bordering strips to lie along and 40 project outwardly from the edge of the fabric, to which said crochet or overedge stitches are applied.

In a separate application filed by me and bearing even date herewith I have described 45 the method of carrying out my invention, the bordering strip being laid upon the face of and fed into the machine with the fabric to which it is to be applied, and as the fabric with its bordering strip passes through

the machine, the usual overedge or crochet 50 binding being produced upon the fabric, the binding having a chain along the edge of the fabric, and loops or stitches extending inward from this chain to a point some distance from the edge of the fabric and over- 55 lapping and confining the inner bar or base portion of the bordering strip, as shown in the drawings, the bordering strip having between the cross bars or pillars openings through which these inwardly-projecting 60 loops or stitches pass, and through which a ribbon can be subsequently threaded. As the crochet or overedge binding is formed by drawing stitches first from one side of the fabric *y* and then from the other side of 65 the same, there is nothing whatever to prevent the bordering strip from being drawn completely out to the edge of the fabric, so that the base of the strip lies along said edge and is confined between the same, and 70 the row of stitches forming the outer boundary of said crochet or overedge binding, as shown in the enlarged diagram, Fig. 2. The bordering strip has therefore the same appearance as though crocheted directly upon 75 the fabric; but owing to the fact that it is made independently and upon a special machine it can be produced very rapidly and at slight expense, and, as it is secured to the fabric by means of a plain crochet or 80 overedge binding upon the latter, the operation can be performed much more expeditiously than when the ornamental border itself is formed by the crochet-machine. Moreover, great variety in the pattern of the outer 85 or ornamental portion of the border is possible, whereas any attempt to produce a variety of patterns by the crochet-machine itself is out of the question, as each pattern requires a special operation of the machine 90 and special mechanism for effecting such operation.

I therefore claim and desire to secure by Letters Patent—

The within-described border or trimming 95 for the edges of fabrics, the same consisting of a strip comprising a straight inner bar lying close to but beyond the edge of the

fabric, an outer scalloped or ornamental edging, and spaced cross bars or pillars connecting said inner bar to the outer portion of the strip, with overedge or crochet stitches,
5 whereby the inner bar of the strip is confined to the edge of the fabric, substantially as specified.

In testimony whereof I have signed my name to this specification in the presence of two subscribing witnesses.

ROBERT W. SCOTT.
